HYDRAULIC POWER UNIT

Edward M. Pfauser, Elm Grove, Wis., assignor to
 Blackhawk Mfg. Co., Milwaukee, Wis., a corporation of Wisconsin

Application August 2, 1937, Serial No. 156,860

3 Claims. (Cl. 103—171)

This invention relates to an improvement in hydraulic power units of the type wherein the pump, release valve and reservoir are incorporated in one unit, from which the liquid, usually oil, is pumped through flexible hose or tubing to one or more rams located at points remote from the unit.

Generally speaking, the object of the invention is to simplify and compact the construction of a unit of this character, improve its appearance, facilitate its operation and enhance its efficiency, its capacity for its intended use and its adaptability for a variety of applications.

More specific objects of the invention are to minimize the possibility of oil leakage and reduce to a minimum the disadvantage of any leakage that does occur; provide for positive pump operation and a positive pressure drive at all handle or lever speeds; prevent the possibility of air being drawn into the pump on its suction stroke and consequent air binding; so control the ram lowering operation as to prevent, for all practical purposes, its accidental or unintentional operation; render the various elements of the unit readily accessible for purposes of adjustment, replacement or repair and this without loss of oil; construct the unit externally as to avoid the accumulation of dirt, snow or water thereon and preclude the possibility of the operating handle or lever freezing in place; and make practical the installation and the convenient operation of the unit in any one of a plurality of different positions.

In carrying out the present invention, the hydraulic power unit is made up of two main elements, namely, a reservoir and a head. The reservoir contains the supply of oil and has a single opening in what is ordinarily its top wall. In the assembly, the head is releasably secured to the reservoir and closes and seals its opening. The pump, the operating means therefor, the intake and outlet or delivery pipes, the passages through which the oil flows from the intake pipes to the pump and from the pump to the outlet or delivery pipes, the valves which regulate the oil flow through these passages, the return passage from the outlet pipe to the reservoir and the release valve which controls the flow through the return passage to the reservoir are all combined with the head and constitute one unitary structure which may be applied to and removed from the reservoir as a unit. This construction increases and in fact more than doubles the oil capacity of the unit and makes it convenient to

interchangeably employ pump and control instrumentalities of various types and sizes.

To adapt the unit for convenient installation in crowded quarters, the head is interrelated with the reservoir for angular adjustment and these parts may be releasably secured together in any one of a plurality of different relative angular positions. Furthermore, the intake pipes are so related to the reservoir and so combined with the head and the unit is otherwise so constituted that while the unit may be and usually is mounted upright, that is, with the head at the top of the reservoir, it also may be turned over on one side with the head vertically disposed; and yet the intake pipes extend to the low point in the reservoir and the unit may be conveniently operated in both positions.

The pump is combined in a special way with the head in that the cylinders are disposed on the inner side of the head and within the confines of the space enclosed by the reservoir and head. Hence should any leakage from the cylinders occur, the leaking oil will drain back into the reservoir and will not be lost and incidentally will not dirty or soil the unit or its environment. In fact, with the various elements of the unit built into the head in the manner described the number of threaded connections under pressure and exteriorly exposed are reduced to a minimum and such as are employed are with the head, hence above the oil level in the reservoir, and are readily made liquid tight.

Where the unit is to be employed to serve selectively a plurality of rams the head is designed to be connected up with the requisite number of outlet or delivery pipes, communication of which with the common outlet passage from the pump is controlled by individual manually operable valves.

Other objects and advantages reside in certain novel features of the construction, arrangement and combination of parts which will be herein-after more fully described and particularly pointed out in the appended claims, reference being had to the accompanying drawings forming a part of this specification and in which:

Figure 1 is a view in top plan showing a hydraulic power unit embodying the present invention;

Figure 2 is a view in longitudinal vertical section taken on line 2—2 of Figure 1, parts being broken away and parts being shown in elevation for the sake of simplicity in illustration;

Figure 3 is a fragmentary sectional view taken on line 3—3 of Figure 1 with parts shown in elevation for the sake of illustration;

Figure 4 is a view in top plan of the head of the unit and a fragment of the outlet or delivery pipe connected therewith and illustrating the passages in the head in dotted lines;

5 Figure 5 is a view in bottom plan of the head of the unit with a similar showing of the passages and with the intake pipes shown in cross section;

10 Figure 6 is a view illustrating the head of the unit and its intake pipes in end elevation and showing the reservoir in transverse vertical section;

15 Figures 7 and 8 are fragmentary views in vertical cross section taken on lines 7-7 and 8-8 respectively of Figure 4; parts being shown in end elevation for the sake of illustration;

20 Figure 9 is a view in horizontal cross section taken on line 9-9 of Figure 6 and illustrating the construction of the cylinders and the passages leading thereto;

25 Figure 10 is a group view in perspective illustrating the double plunger, the rocker arm which actuates the same and a fragment of the operating lever;

30 Figure 11 is a view in top plan showing a modified form of head designed to be employed with a unit of this type where the unit serves a plurality of rams;

35 Figures 12, 13, 14 and 15 are views in vertical section taken on lines 12-12, 13-13, 14-14, 30 and 15-15 of Figure 11; and

40 Figure 16 is a view in end elevation of this modified form of head.

45 Referring to the drawings and more particularly to Figures 1 to 10 inclusive it will be seen that the hydraulic power unit there shown comprises generally a reservoir R and a head H.

The reservoir R comprises a metal receptacle of oblong form comprising a bottom wall 1, a vertical peripheral wall 2 integral therewith and a horizontal top wall 3 provided with a central opening 4 and formed with an annular flange 4 around the margin of the opening. Apertured attaching flanges 5 may be integrally formed with the reservoir to facilitate the mounting and 50 securing of the reservoir in position at the point of use.

The head H comprises a casting which in the structure shown is of circular outline, is formed with an inset and downwardly projecting peripheral wall 6 designed to snugly fit into the flanged opening 4 and with an outwardly extending annular flange 7 which overlies the top of the flange 4 and is releasably secured thereto in any suitable way, as for example, by screws 8. A gasket 9 is 55 interposed between the flanges 4 and 7 so that when the head is applied and fastened down it serves to close the opening 4 and seal the reservoir. With this construction the head may be angularly adjusted with respect to the reservoir 60 and by providing the flange 4 with a greater number of openings or bolt holes 12 than the flange 7 it is practical to releasably secure the head H in any one of a number of different angular positions relative to the reservoir. This is 65 advantageous when mounting the unit in crowded quarters.

70 Integral with the underside of the head H are axially spaced and aligned cylinders 10 and 11. The cylinders are open ended but in the assembly their outer ends are closed and sealed by plugs 12 threadedly connected therewith as shown in the drawings. However, should any oil leak past the plugs it is apparent that it will find its way back into the reservoir since the cylinders and 75 their plugs are entirely contained in the space

enclosed by the reservoir R and head H. A wall or web 13 is integral with the inner or adjacent ends of the cylinders 10 and 11 and with the head and coacts with the head to define a chamber or well 14 closed at its bottom and at its sides although directly communicating with opening 15 which extends up through the top of the head.

5 A double plunger designated generally at 16 is operatively fitted in the cylinders 10 and 11, the plunger including plunger members 17 and 18 and a notched or flattened connecting portion 19 integral with these plunger members. Each plunger member has its outer end provided with a reduced extension 20. On each reduced extension 20 a packing cup 21 is fitted. The outer portion of each reduced extension is threaded and with this threaded portion nuts 22 are engaged, the inner nut pressing against a metallic spreader 23 interposed between the inner nut 22 and the adjacent face of the cup 21.

20 For the purpose of reciprocating the plunger in the cylinders 10 and 11 a rocker arm designated generally at 25 is provided and has a ball

25 26 engaging a seat 27 which is supported on a shoulder 28 formed at the juncture of the opening 15 and space 14. The inner end of the rocker arm is bifurcated as at 29 and its spaced arms 30 straddle the notched or flattened connecting portion 19 of the plunger 16. At the junctures of the connecting portion 19 and the plunger members 17 and 18 shoulders 31 are presented and when the rocker arm is assembled with this plunger the rounded faces 30' of its arms 30 bear against these shoulders. The ball 26 is held in position on its seat 28 by means of a packing nut 32 threaded to the head, as shown in Figure 2. A packing washer 33 is interposed between the packing nut 32 and the seat 27. The nut 32 closes the outer end of the opening 15 and is substantially flush with the adjacent portion of the top of the head and eliminates the deep well effect and hence prevents the accumulation of dirt, water, snow or ice and avoids the possibility of the operating lever or handle freezing in place.

30 The outer portion of the ball 26 is provided with an internally threaded socket into which the lower threaded end of an operating lever or handle 35 is threaded in the assembly. The outer end of the lever 35 may be equipped with a knob 36 after the manner of a gear shift lever. The knob 36 fits the hand and together with the ball and socket mounting or fulcrum for the lever 35 makes pumping easier.

35 With this construction, when the lever 35 is rocked, the plunger 16 is reciprocated to cause the pump to draw oil from the reservoir to force it under pressure to the ram or rams in a manner which hereinafter will more clearly appear.

40 The outer ends of the cylinders draw their oil from a low point in the reservoir and to accomplish this intake pipes 37 and 38 are provided, the intake pipes having their upper ends threadedly connected with the underside of the head H adjacent to but laterally offset from the cylinders 10 and 11 respectively and in direct communication with vertical passages 39 and 40 provided in the head (see Figure 3).

45 As shown in Figures 2, 3, 6 and 7 the intake pipes 37 and 38 are angled so as to extend from the head H down to a point adjacent one of the bottom corners of the reservoir. This so disposes the lower extremities of the intake pipes that they are located at the low point of the reservoir not only when the unit is positioned upright but also when it is turned over on one of its sides.

The suction and discharge valves for regulating the action of the twin pumps are located in the vertical passages 39 and 40 and as they are identical a single description will serve for both. As shown to advantage in Figure 3 suction valves 41 are provided in the passages 39 and 40 and preferably are the simple ball valves biased to engage their seats under the influence of gravity. The discharge valves 42 are also ball valves and are located in the passages 39 and 40 above the suction valves 41. These discharge valves 42 are biased into engagement with their seats by gravity and also by means of light coil springs 43, the lower ends of which bear down against the discharge valves and the upper ends of which abut cap screws 44 threaded into the enlarged upper ends of the passages 39 and 40 for closing and sealing the same. By removing the screws 44 access is readily had to the suction and discharge valves.

In between the suction and discharge valves 41 and 42 the passages 39 and 40 communicate with horizontal passages 45 and 46 (see Figure 9). These passages 45 and 46 extend from the passages 39 and 40 to the outer ends of the cylinders 10 and 11 respectively and are in direct communication with these cylinders. Above the discharge valves 42 the passages 39 and 40 are cross connected by a main outlet passage 47, the ends of which are closed in the manner illustrated in Figure 3.

From the main outlet passage 47 the oil is conducted either to a ram or is returned back to the reservoir and for this purpose the main outlet passage 47 adjacent one of its ends is in open communication with an inclined and transversely extending passage 48 (see Figures 2, 3 and 4) which leads to an opening 49 formed in a boss 50 provided on the upper side of the head. An outlet pipe 51 is threadedly connected with the boss 50, freely communicates with the opening 49 and extends to the ram (not shown) which the unit operates. The other end of the main outlet passage 47 is in open communication with a passage 52 (see Figures 2, 3, 4, 6 and 8) which is also inclined and extends transversely of the head and communicates with axial passage 53 formed in a boss 54 also integrally formed with the head. The axial passage 53 leads to the valve seat 55 of a release valve designated generally at 56. Beyond the valve seat 55 the boss 54 is formed with an opening 53' suitably machined to accommodate the release valve 56. The opening 53' in the boss 54 on the other side of the release valve seat from the passage 53 communicates with a return duct or return passage 57 which extends down through the underside of the head and opens into the reservoir.

The release valve 56 comprises a spindle 58 threadedly engaged with a packing nut 59 which is also threaded into the boss 54. Valve head 60 of release valve 56 is engageable with the seat 55. The nut 59 not only serves as a threaded bearing from the spindle 58 of the release valve but also functions to compress the release valve packing 61. An operating lever 62 is releasably secured to the outer end of the valve spindle 58 and screw 63.

The head H is also provided with a filler plug 65. With this construction when the lever 35 is rocked the plunger 16 is reciprocated. On each reciprocation of the plunger 16 one of its plunger members, for example the plunger member 18, will draw oil into its cylinder 11 while its other plunger member 17 is expelling oil from the

cylinder 10 which has previously been drawn thereto. On the suction stroke of the plunger member 18 oil is pulled up through the intake pipe 38 and vertical passage 40 past the suction valve 41 and through the horizontal passage 46 into the cylinder 11, the discharge valve 42 in passage 40 remaining closed during this phase of the operation under the influence of its bias and of pressure. On the return stroke of the plunger member 18 the oil in the cylinder 11 is expelled out through the passage 46 and up past the discharge valve 42 in passage 40, pressure and gravity maintaining the suction valve 41 in the passage 40 closed at this time. The oil forced up past either discharge valve 42 flows into the main outlet passage 47 and if the release valve 56 is closed it will flow through the passage 52, opening 50, and delivery pipe 51 to the ram. When the release valve is open oil will flow from the main outlet passage 47 through the passages 52 and 53 to the return passage 57 and will drain back into the reservoir. Since the delivery pipe 51 to the ram is in free communication with the outlet passage 47 the ram will be lowered when the release valve 56 is opened.

When the unit is in use the space 14 is partially filled with oil and in this way leakage of air past either plunger member on their suction strokes is prevented. An overflow opening 14' prevents pressures from building up in the space 14.

When the device is not in use the handle 35 and the lever 62 may be readily removed to preclude the possibility of unauthorized persons operating the unit.

In Figures 11 to 16 inclusive a modified head 35 structure designated generally at H' is shown and may be used to advantage where the unit with which it is associated is designed to serve a plurality of rams selectively or simultaneously. The head H' like the head H is circular in outline and is designed to be bolted or releasably secured to the marginal flange of the opening in the top of the reservoir.

Where the parts of the head H' are identical with those of the head H they are designated 45 by the same reference numeral. Thus it will be seen that the head H' has cylinders 10 and 11 integrally formed with its underside with the adjacent ends of the cylinders connected by the web or wall 13. A double plunger 16 is operatively interrelated with the cylinders 10 and 11 and is actuated by a hand lever 35 having a ball and socket mounting in the central portion of the head as before. The oil is supplied to the outer ends of the cylinders through intake pipes 37 and 38 which are connected to the lower ends of the vertical passages designated in this form at 39' and 40' for the reason that they are somewhat longer than the corresponding passages 39 and 40 in the head H due to the increased 60 vertical dimensions of the head H'. However, suction and discharge valves 41 and 42 are combined with these passages 39' and 40' in just the manner above described and these passages 39' and 40' have their portions located between the 65 valves connected to the outer ends of the cylinders by horizontal passages 45 and 46 and above the discharge valves 42 passages 39' and 40' communicate with a main outlet passage designated at 47'. The discharge valve springs designated 70 at 43' are somewhat longer than corresponding springs 43.

This modified head also has the same release valve 56 combined therewith in the manner above described and regulating the return of the oil 75

from the main outlet passage back to the reservoir through a return passage 57 as before.

The principal difference between the head H' and the head H resides in the fact that the head H' has a plurality of outlet fittings designated at 70, 71, 72, 73 and 74 located at spaced points around its periphery and designed to be coupled by suitable pipes or tubing to separate rams.

In the head H' branch outlet passages connect 10 the main outlet passage 47' with the outlet fittings 70, 71, 72, 73 and 74 but the communication of these branch outlet passages with their respective outlet fittings is controlled by hand operated valves 75, 76, 77, 78 and 79 there being one such 15 valve for each outlet fitting. As illustrated in Figures 11 and 14 an intermediate portion of the main outlet passage 47' connects with one end of a radially extending branch passage 80 and the outer end of this branch passage 80 connects 20 with the lower end of a vertically extending passage 81, the upper end of the passage 81 in turn connecting with a transversely extending passage 82 the ends of which terminate in valve chambers 83 of the valves 75 and 76 at points 25 above the valve seats of said chambers.

As shown in Figures 11, 15 and 16 a branch passage 85 extends from one end portion of the main outlet passage 47' up to the passage 53 leading to the release valve and the upper end of 30 this passage 85 also communicates with an inclined passage 86 which leads into the valve chamber of the valve 12 above the valve seat thereof. Branch passages 87 and 88 which are 35 in effect continuations of the branch passage 86 similarly communicate with the valve chambers of the valves 78 and 79.

The valves 75, 76, 77, 78 and 79 are all identical in construction so that a single description will serve for all. Each of these valves has a casing 40 90 formed integral with the head and provided with the valve chamber 91 with which the branch passages communicate, a valve seat 92 at the lower end of this chamber and a short vertical passage 93 leading from the valve seat down to 45 the associated outlet fitting (see Figures 12 and 15). Each valve has a stem 94 provided at its lower end with a beveled head 95 engageable with its valve seat. The upper end of each stem is provided with a hand wheel 96. A portion of the 50 stem is externally threaded as at 97 and engaged with the internal threads of a combined packing and bearing nut 98 which is threaded to the upper end of the casing 90. When the hand wheel 96 of any valve is appropriately turned the 55 valve may be opened or closed. The nut 98 also serves to compress packing 99 with which each valve is equipped.

With a head constructed in this manner the 60 hydraulic control unit may be employed to operate any one ram or any selected number within its capacity. Selection of the rams to be served by the unit is of course, determined by proper adjustment of the valves 75, 76, 77, 78 and 79. However, when these valves are open then the 65 pressure which the pump builds up in the main outlet passage 47' is free to flow to all of the rams, but the communication of any ram with the main outlet passage 47' may be shut off by closing the valve associated with the outlet fitting 70 to which such ram connects.

While the intake pipes 37 and 38 are shown as being separate pipes threadedly connected to the head obviously they may be cast integral therewith or in lieu of a typical pipe structure suitable

extensions of the head may have intake ducts or passages therein.

Then again, while the head is shown and described as being of circular outline, obviously other shapes may be resorted to and many of the advantages of the invention approximated.

While I have shown and described several constructions in which the invention may be advantageously embodied, it is to be understood that the constructions shown have been selected 10 merely for the purpose of illustration or example and that various changes in the size, shape and arrangement of the parts may be made without departing from the spirit of the invention or the scope of the subjoined claims.

The invention claimed is:

1. A hydraulic power unit of the character described comprising a reservoir having an opening, a closure head releasably secured to the reservoir and closing said opening, said head including a marginal attaching flange and a central thickened body portion, said body portion being provided with a central well and a plurality of bores radiating from opposite sides of the well, piston members reciprocable in said bores, means connecting said pistons, said piston connecting means extending transversely through said well, said well opening through the external surface of said head, means within said well for supporting an actuating lever for said pistons, said lever supporting means including a ball member, a depending arm carried by the ball and operatively engaging the piston connecting means, and an operating arm carried by the ball and extending exteriorly of said head through the open end of the well, said thickened body portion of the head being provided with valved intake and discharge passages communicating with said bores and with the interior and exterior of said reservoir, respectively, whereby when the operating arm is oscillated the pistons are reciprocated within their respective bores to pump liquid contained in the reservoir to a point outside thereof.

2. A hydraulic power unit of the character described comprising a reservoir having an opening, a closure head releasably secured to the reservoir and closing said opening, said head including a marginal attaching flange and a central thickened body portion, said body portion being provided with a central well and a plurality of bores disposed generally parallel to the plane of the head and communicating at one end with the well at diametrically spaced points, piston members reciprocable in said bores, means connecting said pistons, said piston connecting means extending transversely through said well, said well opening through the external surface of said head, an upstanding boss surrounding said opening, means within said well and boss for supporting an actuating lever for said pistons, said lever supporting means including a ball member, a depending arm carried by the ball and operatively engaging the piston connecting means, and an operating arm carried by the ball and extending exteriorly of said head through the open end of the well, said thickened body portion of the head being provided with valved intake and discharge passages communicating with said bores and with the interior and exterior of said reservoir, respectively, said intake passages including intake pipes carried by the head and terminating adjacent the bottom of the reservoir, said body portion of the head including upstanding web members on the exterior surface thereof extending radially outwardly from said central boss towards said mar-

- ginal attaching flange, both of said webs being provided with longitudinally extending ducts in communication with each other and with the discharge passages of said bores, one of said ducts serving to deliver the discharge from the bores exteriorly of the reservoir, the other of said ducts being provided with a return passage discharging into the reservoir, and a manually controlled release valve controlling said return passage where-
5 by when said operating lever is oscillated, fluid from within the reservoir may be pumped through the discharge duct when the release valve is closed, or through the return passage when the release valve is open.
- 10 3. A hydraulic power unit of the character described comprising a reservoir having an opening, a closure head releasably secured to the reservoir and closing said opening, said head including a marginal attaching flange and a central thickened body portion, said body portion being provided with a central well and a pair of aligned bores radiating from opposite sides of the well, piston members reciprocable in said bores, means connecting said pistons, said piston connecting
- means extending transversely through said well, said well opening through the external surface of said head, means within said well for supporting an actuating lever for said pistons, said lever supporting means including a ball member, a depending arm carried by the ball and operatively engaging the piston connecting means, and an operating arm carried by the ball and extending exteriorly of said head through the open end of the well, said thickened body portion of the head being provided with valved intake and discharge passages communicating with said bores and with the interior and exterior of said reservoir, respectively, whereby when the operating arm is oscillated the pistons are reciprocated within their respective bores to pump liquid contained in the reservoir to a point outside thereof, said well being provided with an overflow passage discharging into the reservoir, and located above the level of said cylinder bores, whereby to trap fluid leaking past said pistons to effect a seal there-
15 for at the open ends of said bores.
